H. MURCH.

Mop Head.

No. 9,781.

Patented June 14, 1853.

UNITED STATES PATENT OFFICE.

HARVEY MURCH, OF LEBANON, NEW HAMPSHIRE.

MOP-HEAD.

Specification forming part of Letters Patent No. 9,781, dated June 14, 1853; Reissued June 2, 1868,
Nos. 2,957 and 2,958.

To all whom it may concern:

Be it known that I, HARVEY MURCH, of Lebanon, in the county of Grafton and State of New Hampshire, have invented a new and useful Improvement in Mop-Heads; and I do hereby declare that the following is a full and exact description thereof, reference being had to the accompanying drawings, making part of this specification, Figure 1 being a plan of a portion of a mop-handle with my improved mop-head attached; Fig. 2, an end view of the same, a portion being removed; and Fig. 3, a vertical central section thereof.

Like letters designate corresponding parts in all the figures.

A metallic cross-head B, provided with a groove on one side e, and around the ends f, f, is fastened firmly to the mop handle 20 A, by means of a socket b, which fits over the end thereof. A movable binder C, substantially of the form shown in the drawings, slides in the grooved ends f, f, of the cross-head B, while its upper end, or shank, 25 moves in a guide catch a, attached to the mop handle, and is provided with a series of notches c, c, formed (as seen in Fig. 3) so as to allow the binder to be drawn upward but not downward past said catch, 30 against which they are pressed by a spring d, attached to the mop handle beneath said shank of the binder. The lower end of the binder, when drawn completely up, fits into the groove e, of the cross head B; but, when

pushed completely down, leaves a space between itself and said cross-head sufficient to admit the mop, which being inserted therein, the binder is simply drawn upward, (the notches c, c, preventing its return,) till the mop is firmly clasped between said binder 40 and cross-head. And when it is desired to remove the mop from the mop head, the upper end of the binder is to be pressed down against the spring d, until the notches c, c, are freed from the catch a; and then the 45 binder is readily pushed down to set the mop free. This arrangement furnishes a very simple, cheap and easily managed means of fastening the mop in its head.

What I claim as my invention and desire 50 to secure by Letters Patent, is—

My improved mop-head, composed of the fixed cross-head B, which has grooves in its lower side and ends, in combination with the sliding binder C, that terminates in a 55 notched shank c, and passes through the loop a, on the handle A, which serves as a deterrent in consequence of the action of the spring d, on the under side of the said shank, substantially as herein set forth.

The above specification of my improved 60 mop-head, signed and witnessed this 12th day of November, 1852.

HARVEY MURCH.
